Philip Langrehr Keating

UNITED STATES PATENT OFFICE

MORRIS H. BENNETT, OF WATERBURY, CONNECTICUT, ASSIGNOR TO SCOVILL MANUFACTURING COMPANY, OF WATERBURY, CONNECTICUT, A CORPORATION OF CONNECTICUT

RHEOSTAT

Application filed January 14, 1927. Serial No. 161,045.

This invention relates to improvements in variable rheostats such as are generally employed in radio receiving apparatus.

It is desirable in this class of rheostat, which are to control and regulate small currents, that the resistance coil be so mounted that it will be prevented from shifting its position, and it is the especial object of this invention to provide improved means for securing the coil in such manner that it will be maintained in proper position and prevented from shifting. Many attempts have heretofore been made to accomplish this result but they have not been found satisfactory in practice.

A further object of the invention is to produce a rheostat which will be simple in number of parts, cheap in cost of manufacture and easy to assemble.

With the above objects in view and some others which will be obvious to those skilled in the art from the description hereinafter, the invention consists in the features, details of construction and combination of parts which will first be described in connection with the accompanying drawings and then more particularly pointed out.

In the drawings:

Figure 1 is a front elevation of a rheostat embodying the features of the present invention;

Figure 2 is a cross-section on the line 2—2 of Figure 1;

Figure 3 is a sectional view of the rheostat mounted on the front panel of a radio receiving instrument;

Figure 4 is a detail view of the clamp; and

Figure 5 is a view similar to Figure 2 before being drawn into position.

Referring to said drawings:

A coil of any suitable resistance wire A is arranged in close symmetrical loops snugly about a core B of any suitable insulating material, as fibre. The resistance wire may advantageously be arranged in the form of a helix and bent into substantially the form of a circle and it will also be of advantage to have the fibre core of such thickness and material that it will easily bend in the form of a circle 50 to conform with its surrounding resistance

wire. These loops of wire are arranged close together about the core in order that the difference in resistance between succeeding coils of the wire will be slight, thus permitting very close control of the variation in current. The resistance coil will not form a complete circle but space will be afforded between its ends to allow a clamp to be applied for securing together the ends of the fibre core.

A bracket M of any suitable conducting material, as brass, is arranged to act as a support for the fibre core and resistance coil. It will be found advantageous to strike this bracket up from a single piece of metal to form two arms a and b, the former of which lies horizontally within the coil and core and has its inner end c extending slightly beyond the center of the circle formed by the core and resistance. Arm a is provided with an opening near its inner end c, which opening is concentric with the circle. This opening is of such size that it allows threaded portion d of hub or barrel H to be snugly fitted therein, this barrel having a body portion provided with a shoulder e which rests against and is supported on the upper side of said bracket arm a. Hub H will be retained in position with its shoulder against the arm a by nut O.

Hub H may be variously constructed and of any suitable material, that herein illustrated being in one piece, of brass, and having at its upper end a cylindrical portion g extending about half its length, next to which is a screw threaded portion d of slightly less diameter than said cylindrical portion, thus forming a shoulder e and this screw threaded portion in turn terminates in a cylindrical portion k of about the diameter of the body of the screw threaded portion. Hub H is perforated centrally throughout its length 30 to allow spindle l to pass therethrough.

It will be advantageous to so arrange bracket arm b that it will lie at slightly acute angle to the arm a. By arranging the arms a and b of bracket M at a slightly acute angle 35 the pressure on bracket arm a, caused by tightening nut O, produces such a pull on arm b that it causes a kind of lever action on the resistance coil and core by drawing bracket arm b and with it the resistance wire and core 40

secured thereto toward the front panel C thereby holding the rheostat firmly against the panel so as to maintain it in proper position and prevent it from shifting. In this lever action the fulcrum is about at the junction of arms *a* and *b*.

It will also be advantageous to extend arm *b* slightly above resistance wire A to allow it to act as a stop and thus prevent finger F making a complete circuit of said resistance wire.

Arm *b* may be secured in any suitable manner to a supporting plate P, which plate, as shown, is of substantially rectangular shape, its width being slightly greater than that of the core B and having its top and bottom ends turned inward substantially at right angles, to take over the top and bottom of said core B. In the present example, plate P is provided with two holes about equidistant from its ends to register with two similar holes in bracket arm *b*.

At one of the ends of plate P, which plate may be of any suitable conducting material, as brass, will be arranged a terminal *j* for securing thereto one of the lead wires, which terminal it will be advantageous to have made an integral part of plate P, as shown. A second lead wire terminal *f* of any suitable conducting material, as copper, is attached to one end of the resistance wire in any suitable manner, as by inserting its end under some of the terminal coils of the rheostat, which are close together but do not contact, and then soldering it.

The ends of insulating core B, to which the resistance wire has been secured in any suitable manner, as by being tightly pressed against said insulating core, are brought closely together, but not so they will overlap, with the bracket arm *b* on the inner side and plate P on the outer side and held from movement in any suitable manner, as by two or more rivets, which may be advantageously entered from the inside, that is, such rivets will first pass through bracket arm *b*, then through the ends of the insulating core and then through plate P, when the outer, or upsetting ends of said rivets will be clenched against the outside of said plate P, thus securely holding these parts together.

The front panel C of an instrument board, which may be of any suitable construction or material, as, for example, phenol condensation product, has a hole D formed in it of such size and shape that it will act as a bearing for rheostat operating spindle *l*, hereinafter described.

A sliding contact finger F, which may be of any suitable current carrying material as, for example, copper, is also provided. Although this sliding contact may be variously constructed, it will be advantageous to have its inner end substantially circular to conform to the shape of the cylindrical end of hub H on

which it rests. In the central part of this circular base portion an opening, which will advantageously be square or rectangular, to receive the elongated upper end of spindle *l*. Contact finger F is secured in any suitable manner to the upper end of spindle *l*, as for example, by upsetting therein said upper end of spindle *l*, which has passed through the squared hole in the secured end of said contact finger. It will be advantageous to have this finger taper gradually from a substantially broad base portion J extending from its circular shaped end resting on hub H to a substantially narrow portion near its outer end when it abruptly widens to a square end portion G of about its original breadth, this widened square portion being bent in the arc of a circle to furnish a rounded surface for contact on and between the loops of the resistance coil, as shown in Fig. 1. Such construction provides a strong and resilient contact surface capable of easy yet certain action.

It will be of advantage, also, to arrange hub H so as to be slightly less in length than the width of the resistance coil A. In the particular embodiment illustrated herein the hub H has a length substantially equal to that of the combined width of resistance coil A and the thickness of the bracket M. It will be advantageous also to have hub H located centrally of the resistance coil in order that the contact finger may make good contact with all the loops of the resistance coil and also that it be of proper length to allow the sliding contact finger F to bear on each convolution of the resistance coil in such manner that it may readily take the current therefrom.

Any usual dial control knob E may be used to operate the rheostat. Such knob is provided with a central bore *f'* to register with perforation D in front panel C to allow spindle *l* to pass through perforation D and into bore *f'*, where its end *j'* will be secured by a screw to cause end *j'* of spindle *l* to move with said knob, which will in turn cause finger F secured to the opposite end of said spindle to be moved. It will be advantageous to interpose a light fibre washer between front panel C and the rheostat.

What I claim is:

1. The combination with a panel and a rheostat, of a supporting bracket comprising a sheet metal element having arms arranged at an oblique angle to each other, one of said arms being supported against the panel and the other arm supporting the rheostat whereby the rheostat is wedged against the panel by the lever action of said element.

2. The combination with a panel and a rheostat of the type including a circular core member, a wire resistance wound on the core member, an operating spindle arranged concentrically of said core and provided with a finger for engaging the wire, of a sheet metal element having arms arranged at an acute

angle to each other, one of said arms being supported against the panel and the other supporting the rheostat whereby the rheostat is urged against the panel by the lever action of said element, a hub surrounding the spindle and mounted in an opening in the panel, said hub carrying the supported arm of the metal element.

5 In testimony whereof, I have hereunto set
10 my hand.

MORRIS H. BENNETT.
